(57) **CLAIM**

The ornamental design for a glove portion with keyboard adapted to receive a device, as shown and described.

DESCRIPTION

FIG. 1 is a front perspective view of an exemplary embodiment of a glove portion with keyboard adapted to receive a device, in a closed position, showing the new design; FIG. 2 is a front perspective view of the embodiment, in the open position, thereof;

FIG. 3 is a top plan view of the embodiment, in the open position, thereof;

FIG. 4 is a bottom plan view of the embodiment thereof;

FIG. 5 is a lateral side elevation view of the embodiment thereof;

FIG. 6 is the medial side elevation view of the embodiment thereof;

FIG. 7 is the front elevation view of the finger-end portion of the embodiment thereof; and,

FIG. 8 is an elevation view of an open wrist-end portion of the embodiment thereof.

The broken lines in the drawing views are included for the purpose of illustrating unclaimed environment only, and forms no part of the claimed design. The dash-dot broken lines in the drawing views define the bounds of the claimed design and form no part thereof.
